UNITED STATES PATENT OFFICE.

JOSEPH CARMEL, OF NEW YORK, N. Y., ASSIGNOR TO HARRY ALFRED BENKESER, OF NEW YORK, N. Y.

TOY PALETTE.

Application filed May 1, 1923. Serial No. 635,948.

To all whom it may concern:

Be it known that I, JOSEPH CARMEL, citizen of Poland, residing at New York, in the county of New York and State of New York, have invented certain new and useful Improvements in Toy Palettes, of which the following is a specification.

This invention relates to painting, and has special reference to a toy painting outfit particularly designed to be sold at a low price, 10 as for instance in such stores as the well known five and ten cent stores.

One important object of the invention is to provide a novel toy painting outfit in 15 which provision is made for carrying paints, brushes and crayons on a palette like device cut and stamped from sheet material.

A second important object of the invention is the provision of a novel palette cut 20 and stamped from sheet material and having means to hold a paint brush and paints, and being also provided with a crayon holder of novel construction likewise formed from a single piece of sheet material.

With the above and other objects in view, the invention consists of a new article of manufacture wherein the various portions are each formed from sheet material cut and 30 stamped or pressed in a novel manner to provide a toy painter's palette having means to hold disks or cakes of paint, other means to hold a paint brush, and still other means to hold a set of crayons.

In the accompanying drawings forming a part of this specification, a preferred form 35 of the invention is illustrated, and in the several views like characters of reference indicate like parts throughout.

In the drawings—

Fig. 1 is a face view of the palette illustrating the crayons and brush in position.

Fig. 2 is a detail section on the line 2—2 of Fig. 1.

Fig. 3 is a detail section on the line 3—3 of Fig. 1.

Fig. 4 is a detail section on the line 4—4 of Fig. 1.

Fig. 5 is a detail section through the crayon holder on the line 5—5 of Fig. 1.

Fig. 6 is a detail face view of a modified form of the crayon holder.

The invention, in the form herein shown, consists of a piece of sheet material, preferably of metal, although other material may

be used if desired, and this piece of sheet material is cut to form a main or body portion 10, having a palette like outline, and having its periphery beaded as at 11 to prevent cutting the fingers of the users. The 60 usual palette thumb hole 12 is provided, and this is also beaded around its periphery as at 13. Disposed centrally of the body portion 10 is a crayon holder which I form from a single piece of sheet material cut to provide an annulus, and then bent and crimped so that when the operations are finished there is obtained a disk 14 having radial 65 crayon holding pockets 15 formed therein, and open at their outer ends, the inner ends 70 abutting and being closed by the crimping, as shown at 16.

On the periphery of the disk 14 are provided triangular prongs 17 which extend through suitable openings in the main portion 10, and are then bent to retain the crayon holder in place. Spaced around the body of the palette at the end remote from the thumb hole are certain depressions 18 which are formed by stamping or pressing the material, and which constitute a paint cake or disk receiving depression. In each of these depressions, the material is slit to provide a series of pointed prongs 19 which may either be bent upwardly and then inwardly over 75 the edge of a paint disk or cake, or may have the paint disk or cake molded thereon. At one place the body 10 is provided with a circular opening 20 wherein fits a shallow 80 water pan 21 having a peripheral flange 22 so that it cannot slip through the opening. This water pan is likewise stamped from a single piece of the sheet material. It is obvious that there may be as many of the 85 paint receiving depressions, and as many water pans as is found desirable in practice. In addition to this one or more brush holders are provided, there being but one shown in the present instance, although it is obvious that the number may be multiplied to 90 suit the requirements of the case. Each of these brush holders is formed of a pair of U-shaped slits arranged in alignment with their closed ends toward each other, but spaced to provide a bridge piece 23. The 95 material defined by the U-shaped slits thus constitutes opposed tongues which are bent downward, as best shown in Fig. 3, one of the tongues being indicated at 24, and receiving the butt end of a brush, while the 100 105 110

other tongue is shown at 25 and receives the front or brush end of such brush.

In the form shown in Fig. 6, the crayon holder is provided with tubes which are slit 5 in the manner shown at 26 for the better gripping of the crayons.

It will be obvious that a device constructed in this manner can be made very cheaply, and is thus highly suitable for the purpose 10 of a toy painting outfit, and it will also be obvious that the particular form and construction may be modified to suit various purposes and costs. It is not therefore desired to confine the invention to the exact 15 form herein shown and described, but it is wished to include all such as properly come within the scope claimed.

Having thus described the invention, what is claimed as new, is:

- 20 1. A toy palette comprising a flat palette shaped main portion formed from a single piece of sheet material, said material having a pair of substantially U-shaped slits formed therein in alinement, the closed ends 25 of the U's being arranged opposite each other in spaced relation whereby to form a bridge piece between the slit portions, the portions defined by said slits constituting tongues and being bent downward to form 30 rests for the ends of a brush held beneath the bridge piece.

2. A toy palette comprising a flat palette shaped main portion formed from a single piece of sheet material and having certain portions adjacent its periphery dished to 35 form shallow paint cake receiving depressions, each of said depressions having a series of upstanding prongs struck from the sheet material to engage a paint cake, and a crayon holder provided with radial 40 crayon pockets and fixed to the main portion.

3. A toy palette comprising a flat palette shaped main portion formed from a single piece of sheet material and having certain 45 portions adjacent its periphery dished to form shallow paint cake receiving depressions, each of said depressions having a series of upstanding prongs struck from the sheet material to engage a paint cake, a 50 crayon holder provided with radial crayon pockets and fixed to the main portion, said crayon holder consisting of a single annulus of sheet material crimped and bent to form said pockets and provided with peripheral prongs extending through the main portion and bent to hold the crayon holder 55 on the main portion.

In testimony whereof I hereunto affix my signature.

JOSEPH CARMEL.
